GAME BOARD OR THE LIKE

John A. Waer, Las Vegas, Nev.

Application December 17, 1951, Serial No. 17,766

Term of patent 14 years

(Cl. D34—5)

To all whom it may concern:

Be it known that I, John A. Waer, a citizen of the United States of America, residing at Las Vegas, in the county of Clark, State of Nevada, have invented a new, original, and ornamental Design for a Game Board or the like, of which the following is a specification, reference being had to the accompanying drawings, forming a part thereof:

I claim:

The ornamental design for a game board or the like, substantially as shown and described.

JOHN A. WAER.
